UNITED STATES PATENT OFFICE.

GEORGE A. ENSIGN AND HERBERT D. TRAUB, OF DEFIANCE, OHIO, ASSIGNEES TO
DEFIANCE MACHINE WORKS, OF DEFIANCE, OHIO, A CORPORATION OF OHIO.

WOOD-TURNING MACHINE.

1,281,771.

Specification of Letters Patent. Patented Oct. 15, 1918.

Application filed September 25, 1917. Serial No. 193,113.

To all whom it may concern:

Be it known that we, GEORGE A. ENSIGN and HERBERT D. TRAUB, both citizens of the United States, and residents of Defiance, in the county of Defiance and State of Ohio, have invented a new and Improved Wood-Turning Machine, of which the following is a full, clear, and exact description.

The invention relates to wood turning machines designed for reducing a rotating stick to other than a circular cross section, and wherein a rotating cutter head rotates in fixed bearings and the rotating stick is caused to approach or recede from the cutter head by means of pattern guides.

The object of the invention is to provide a new and improved wood turning machine of the type mentioned and more especially designed for turning a portion of a stick to form a shank of oval cross section to form a head at one end of the stick and to provide a throat between the head and the shank thus producing such articles as spokes for use on wheels for automobiles and other vehicles. Another object of the invention is to render a wood turning machine which after the material is moved into centering position is completely automatic in its actions and to insure the production of a large amount of turned articles in a comparatively short time and without requiring skilled labor.

In order to accomplish the desired result use is made of revoluble cutting means and an intermittently rotating work holder provided with revoluble stick holding means engaging the ends of a stick while the latter is at rest, carrying the stick bodily into engagement with the said cutting means for the latter to reduce the stick while the said work holder is at rest and the stick is rotated by the said revoluble stick holding means, and finally carrying the reduced stick from the said cutting means to a discharge position and releasing it to allow the reduced stick to drop.

A practical embodiment of the invention is represented in the accompanying drawings forming a part of this specification in which similar characters of reference indicate corresponding parts in all the views.

Figure 1 is a plan view of the wood turning machine;

Fig. 2 is a front elevation of the same with parts shown in section; 55

Fig. 3 is an enlarged elevation of the left hand end of the wood turning machine with part of the spindle drum broken out;

Fig. 4 is a similar view of the right hand end of the same. 60

Fig. 5 is an enlarged cross section of the wood turning machine on the line 5—5 of Fig. 1;

Fig. 6 is an enlarged sectional plan view of the same on the line 6—6 of Fig. 5; 65

Fig. 7 is an enlarged cross section of the drum carrying the centers, the section being on the line 7—7 of Fig. 1;

Fig. 8 is an inner face view of one of the heads of one of the drums. 70

Figs. 9 and 10 are plan views of the lever bearings in which the spindles and centers are journaled;

Fig. 11 is a plan view of the spoke produced by the wood turning machine; and 75

Fig. 12 is a side elevation of the same.

The stick 10 of approximately square cross section (see Fig. 5) is reduced by the wood turning machine to form a shank 11 of oval cross section, a throat 12 and a head 13 of rectangular cross section (see Figs. 11 and 12). For forming the shank 11 and the throat 12 use is made of a revoluble cutter head 14 and for forming the head 13 use is made of a revoluble cutter head 15. The shafts 16 and 17 of the cutter heads 14 and 15 are parallel and are journaled in suitable bearings 18 and 19 mounted on the frame 20 of the wood turning machine. On the shafts 16 and 17 are secured pulleys 21 and 22 connected by belts with other machinery for continually rotating the said shafts 16 and 17 and their cutter heads 14 and 15. By reference to Figs. 1 and 6 it will be noticed that the cutter head 14 is provided with the usual knives 23 having straight cutting edges for forming the shank 11, and a set of knives 24 with rounded ends for forming the throat 12, and this set of knives is arranged in overlapping relation to a set of knives 25 of the cutter head 15 used for forming the head 13. 95

The sticks 10 are held one in front of the

other on a support formed of two horizontal plates 30 provided with side flanges 31 and rear end flanges 32, of which the latter serve to limit the inward movement of the innermost stick 10 (see Figs. 1 and 5), and the side flanges 31 hold the sticks against longitudinal movement but terminate a distance from the end flanges 32 and clear the innermost stick 10, as will be readily understood by reference to Figs. 1 and 3. The supporting plates 30 are engaged by the bolts 33 extending through transversely extending slots 34 formed on flanges 35 of vertical arms 36 provided with vertical slots 37 engaged by bolts 38 screwing in standards 39 mounted to slide longitudinally on a guideway 40 formed or attached to the main frame 20. On loosening the bolts 38, the arms 36 and with them the supporting plates 30 can be raised or lowered, and by loosening the bolts 33 the supporting plates 30 may be adjusted in a transverse direction. In order to aid in the vertical adjustment of the arms 36 use is preferably made of bolts 41 screwing on the standards 39 and engaging the lower ends of the arms 36. Jam nuts 42 serve to lock the adjusting bolts 41 in place after the desired adjustment is made. The standards 39 are fastened in place on the guideways 40 by suitable set screws 43 which when loosened permit of moving the standards toward or from each other according to the length of the sticks to be reduced at a time by the cutter heads 14 and 15. The transverse adjustment of the supporting plates 30 is for the purpose of properly moving the rearmost stick 10 into centering position, as hereinafter more fully explained.

The rear ends of the supporting plates 30 extend between drums 50 and 51 forming part of an intermittently rotating work holder adapted to pick up the rearmost stick 10 at the ends thereof, carrying the stick bodily in engagement with the cutter heads 14 and 15 for the latter to reduce the stick while the work holder is at rest and the stick is rotated, and finally carrying the reduced stick from the cutter head 15 to a discharge position and releasing the reduced stick to allow the same to drop. The drums 50 and 51 are provided with heads 52, 53 and 54, 55, of which the opposite heads 53 and 54 are centrally and adjustably connected with each other by a sleeve 56 to cause the drums 50 and 51 to rotate intermittently in unison and to allow of adjusting the drum 51 nearer to or farther from the drum 50, for reducing sticks of different lengths, as hereinafter more fully explained. One end of the sleeve 56 is rigidly secured to the hub of the head 53 and the other end slidably engages the hub of the head 54 by a key 57 and a keyway 58, and a set screw 59 is used to fasten the sleeve 56 to the head 54 after the desired adjustment is made.

In order to intermittently rotate the drums 50 and 51 use is preferably made of a Geneva driving and locking movement consisting essentially of a star wheel 60 attached to the outer head of the drum 50 and periodically engaged by a friction roller 61 journaled on an arm 62 secured on a shaft 63 journaled in suitable bearings arranged on the main frame 20. On the shaft 63 is secured a gear wheel 64 (see Fig. 1) in mesh with a pinion 65 secured on a shaft 66 journaled on the main frame 20. On the shaft 66 is secured a gear wheel 67 in mesh with a pinion 68 secured on a main driving shaft 69 journaled on the main frame 20 and connected by a belt with other machinery for imparting a continuous rotary motion to the main driving shaft 69. The rotary motion of the main driving shaft 69 is transmitted by the gearing described to the shaft 63 carrying the arms 62, which latter by the friction roller 61 periodically engaging the star wheel 60 rotates the drum 50 and its companion drum 51 intermittently. The arm 62 is provided with a segmental wheel portion 71 engaging the peripheral face of the star wheel 60 to hold the latter in locked position while at rest thus preventing accidental turning of the drums 50 and 51 during the period of rest.

On the drums 50 and 51 are mounted sets of spindles and centers 80 and 81, of which the spindle and center of a set have their axes coinciding, and the axes of the sets of spindles and centers are spaced equal distances apart and arranged in circles, the centers of which coincide with the centers of the drums 50 and 51. The spindles 80 are journaled in bearings 82 formed on levers 83 (see Figs. 8, 6, 9 and 10) fulcrumed loosely on shafts 84 mounted in the heads 52, 53 of the drum 50. The levers 83 are pressed on by springs 85 attached to the inner surfaces of the heads 52, 53 of the drum 50. On each of the spindles 80 is secured a pinion 86 in mesh with an intermediate gear wheel 87 mounted on the shaft 84 and in mesh with a pinion 88 secured on a shaft 89 journaled in the heads 52, 53 of the drum 50. The pinion 88 is in mesh with a gear wheel 90 secured on a continually rotating shaft 91 journaled centrally in the heads 52, 53 and 54, 55 of the drums 50 and 51. On the left-hand end of the shaft 91 is secured a gear wheel 92 (see Figs. 1 and 3) in mesh with an intermediate gear wheel 93 mounted on a stud 94 attached to the main frame 20. The gear wheel 93 is in mesh with a pinion 95 secured on the shaft 66 previously mentioned and continually driven from the main driving shaft 69. Thus when the latter is rotated a continuous rotary motion is given to the shaft 91 by the gearing described. The drum shaft 91 is journaled in bearings 96 and 97, of which the bearing 96 is

fastened to the main frame 20 while the bearing 97 is longitudinally adjustable on guideways 98 attached or formed on the main frame 20 (see Figs. 2 and 4).

5 The centers 81 are journaled in bearings 100 formed on levers 101 fulcrumed loosely on shafts 102 journaled in the heads 54, 55 of the drum 51. The levers 101 are pressed on by springs 103 attached to the inner surface of the heads of the drum 51. On the centers 81 are secured pinions 104 in mesh with intermediate pinions 105 held on the shafts 102 and in mesh with pinions 106 secured on shafts 107 journaled in the heads 15 of the drum 51. The pinions 106 are in mesh with a gear wheel 108 secured on the shaft 91 previously mentioned. From the foregoing it will be seen that when the shaft 91 is rotated the two sets of gearings described 20 rotate the spindles 80 and the centers 81 continually.

The spindles 80 pass through slots 110 formed in the inner head 52 of the drum 50, and the spindles 81 extend through slots 111 25 and 112 formed in the heads 53, 54 of the drum 51, the slots 112 having narrow extensions 113 for guiding purposes, as herein-after more fully explained.

On the spindles 80 and the centers 81 are 30 secured patterns 120 and 121 of oval shape and adapted to engage guides 122 and 123 attached to transverse arms 124 and 125 held longitudinally adjustable on pins 126, 127, 128 and 129 mounted on the main frame 35 20. The arms 124 and 125 are fastened in place after the desired adjustment is made by the use of set screws 130 and 131 screwing on the arms against the pins 126 and 128, as will be readily understood by reference to 40 Fig. 6. By the arrangement described the patterns 120 and 121 move accurately in engagement with the pattern guides 122, 123. The pattern guides 122 and 123 are disposed on opposite sides of the cutter head 14 and 45 are arranged in such relation thereto (see Fig. 5) that the knives 23 and 24 of the cutter head 14 reduce a portion of the stick 10 to form a shank 11 of oval cross section corresponding to the shape of the patterns 120 50 and 121. On the spindles 80 and the centers 81 are secured adjacent the oval patterns 120 and 121 the rectangular patterns 140 and 141 adapted to engage pattern guides 142 and 143 mounted on arms 144 and 55 145 (see Fig. 2) each adjustably mounted on pins 146 and 147 attached to the main frame 20. As this arrangement is the same as above described in relation to the guides 122 and 123 and their arms 124 and 125 60 further description of the pattern guides 142 and 143 is not deemed necessary, it being, however, understood that the pattern guides 142 and 143 are arranged on opposite sides of the cutter head 15 to cause the 65 knives 25 of this cutter head to reduce the

end of the stick with a view to form the said end into a head 13 rectangular in cross section, as will be readily understood by reference to Fig. 5. As illustrated in the drawings, four sets of spindles 80 and centers 81 70 are used and the drums 50 and 51 are stepped forward intermittently four times during each revolution, the star wheel 60 being shaped correspondingly (see Fig. 3) and the arm 62 being correspondingly rotated from 75 the main driving shaft 69 by a properly proportioned gearing connecting the shaft 69 with the shaft 63. The cutter heads 14 and 15 and the pattern guides 122, 123 and 142, 143 are positioned in such a manner that 80 when one stick is reduced by the cutter head 14 another stick is reduced by the cutter head 15.

By mounting the spindles 80 and the centers 81 in the bearings 82 and 100 of the 85 rocking levers 83 and 101 the stick is allowed to readily advance and recede relative to the cutter heads for the latter to reduce the stick in the manner described and without stopping the rotation of the said spindles 80 and 90 centers 81 and while the drums 50 and 51 are at rest. It is further understood that the spindles 80 and the centers 81 are carried bodily around with the drums 50 and 51 owing to the levers 83 and 101 being fulcrumed 95 in the drums 50 and 51.

The spindles 80 have no movement in the direction of the length of their axes but the centers 81 are periodically moved in the direction of the axes to engage one end of a 100 stick while the latter is at rest on the supporting plates 30, and to release the reduced stick during the time the latter travels from the cutter head 15 toward the front. In order to impart this periodical sliding movement to the spindle 81 the following arrangement is made: The spindles 81 are mounted to slide in the bearings 100 of the levers 101 and are provided with keys 150 engaging keyways in the pinions 104 held against 110 movement in the direction of their axes by being held between the double bearings 100 (see Fig. 6). Each center 81 is provided outside of the drum 51 with two collars 154, 155 (see Fig. 6), of which the collar 154 engages an arm 156 mounted on the corresponding center 81 and provided with a friction roller 157 adapted to engage a cam 158 (see Fig. 4) adjustably secured by bolts 159 to a bracket 160 attached to the bearing 97. 120 The bolts 159 extend through slots 161 formed on the cam 158 to permit accurate adjustment of the cam. The cam 158 is provided at its lower end with an incline 162 to cause the friction roller 157 to gradually 125 travel up said incline with a view to exert an outward pressure on the collar 154 to move the corresponding center 81 in an outward direction for disengaging the center from the corresponding end of the reduced stick 130

at the time the latter moves from the cutter 15 toward the front. The upper end of the cam 158 is abrupt to allow the friction roller 157 to suddenly drop off the cam with a view 5 to engage the corresponding center 81 centrally with the end of the stick 10 in innermost position at the time on the supporting plates 30.

In order to impart a quick and forceful 10 inward sliding movement to a center 81 at the time the friction roller 157 drops off the upper end of the cam 158, use is made of powerful springs 170 attached to the outer head 55 of the drum 51 and connected with 15 a crosshead 171 bearing against the collar 155 of the corresponding center 81. It is understood that while the drums 50 and 51 are rotating the corresponding centers 81 are released by the friction roller 157 dropping 20 off the upper end of the cam 158 and the center 81 is forced inward by the action of the springs 170 and the crosshead 171 to engage the center with the corresponding end of the stick 10 in innermost position at the 25 supporting plates 30, thus forcing the other end of the stick in engagement with the spindle 80. Thus the stick is engaged by the corresponding pair of spindles 80 and centers 81 lifted off the supporting plates 30 and carried upward and rearward during 30 this turning period of the drums 50 and 51. The arms 156 are held against turning by pins 175 projecting into the elongated portions 113 of the slots 112 through which extend the centers 81, as previously explained. 35 The hub of each cam arm 156 is preferably rigidly connected by a sleeve 176 with the corresponding crosshead 171 (see Fig. 6) and between the said hub of the cam arm 40 156 and the collar 154 is arranged a washer 177 of leather or other similar material, and a similar washer 178 is interposed between the collar 155 and the crosshead 171. On the inner face of the hub of the cam arm 156 is 45 arranged a washer 179 of leather or similar material adapted to abut against the outer face of the outer head 55 of the drum 51, as plainly shown in the upper portion of Fig. 6. It will be noticed that by the arrangement 50 described the sliding movement of the centers 81 from the right to the left is limited by the washers 179 abutting against the head 55 after the friction rollers 157 have left the upper end of the cam 158.

55 When the reduced stick is dropped by the corresponding center 81 moving from the left to the right then such reduced stick drops down onto the upper run of an endless conveyer belt 190 passing around pulleys 191 and 192 having their shafts 193 and 194 journaled in suitable bearings arranged on the main frame 20, as plainly shown in Figs. 1, 2, 3, 4 and 5. The shaft 193 is provided with a bevel gear wheel 195 in mesh with 60 a bevel gear wheel 196 secured on the lower

end of a vertically disposed shaft 197 journaled in suitable bearings arranged on the main frame 20. The upper end of the shaft 197 is provided with a bevel gear wheel 198 in mesh with a bevel gear wheel 199 secured 70 on the drum shaft 91 to rotate with the same. Thus when the machine is running and the shaft 91 is rotated as previously described then a traveling motion is given to the conveyer belt 190 to carry the dropped 75 reduced stick to one side of the machine.

In order to prevent the stick from being accidentally displaced on the upper run of the conveyer belt 190 use is made of side guides 200 and 201 attached to the main 80 frame 20 and extending upwardly on opposite sides of the upper run of the conveyer belt 190. The guide 201 is provided with an upwardly and rearwardly extending member 202 intermediate the drums 50 and 85 51 to a guide a dropped stick to the upper run of the conveyer belt 190, as will be readily understood by reference to Fig. 5.

In order to adapt the machine for reducing longer or shorter sticks 10, it is necessary to correspondingly move the drums 50 and 51 farther apart or nearer to each other and for this purpose the drum 51 is moved bodily from or toward the other drum 50 after the set screw 59 is loosened. For the purpose mentioned the outer end of the hub of the head 55 (see Fig. 6) is provided with an annular groove 210 engaged by a lug 211 of a plate 212 secured to the top of the bearing 97 so that the drum 51 moves with the bearing 97 when the latter is adjusted in a longitudinal direction. The bearing 97 is provided with a nut 213 (see Fig. 2) in which screws a screw rod 214 mounted to turn in a bearing 215 secured to or forming 100 part of the main frame 20. The screw rod 214 is held against movement in the direction of its length by two collars 216 secured on the screw rod and abutting against opposite sides of the bearing 215. The outer end of the screw rod 214 is provided with a hand wheel 217 to permit of conveniently turning the screw rod 214 with a view to move the bearing 97 to the right or to the left with a view to move the drum 51 away 115 from or toward the other drum 50 according to the length of the stick to be reduced at the time. The bearing 97 is fastened in place on the main frame 20 after the desired adjustment is made by the use of a screw 220 120 screwing in the main frame 20 and extending through a longitudinal slot 221 formed in the bearing 97. The set screw 59 is also tightened up after the desired adjustment is made.

125 The operation is as follows:

When the machine is running the cutter heads 14 and 15 are continually rotated in the direction of the arrows indicated in Figs. 3 and 5, the drums 50 and 51 are inter- 130

mittently rotated in the direction of the arrows indicated in Figs. 3 and 5, and a continuous traveling motion is given to the endless conveyer belt 190. The drums 50 and 51 are at rest when in the position shown in Fig. 5 and the cutter head 14 now reduces one stick to form the shank 11 and the throat 12, and the cutter head 15 reduces one end of another stick to form the head 13 adjacent the throat 12. A stick 10 is held on a pair of spindles 80 and centers 81 above the supporting plates 30, and a reduced stick is in the act of dropping from a corresponding pair of spindles and centers 80 and 81, the dropped stick eventually falling onto the belt 190 to be carried to one side of the machine. During the next quarter revolution of the drums 50 and 51, the partly reduced stick at the cutter head 14 is moved in position relative to the cutter head 15 and the last reduced stick is carried forward and dropped to fall onto the conveyer belt 190, and the stick 10 carried by the uppermost pair of spindles and centers 80 and 81 is carried into active position at the cutter head 14 to be reduced by the latter as previously explained. During this quarter revolution of the drums 50 and 51 the lower front center is moved outward to the right to release the reduced stick and the center is held in this position until the corresponding friction roller 157 drops off the end of the cam 158 so that the springs 170 impart a sudden and forceful movement to the center from the right to the left to engage the point of the center 81 with the middle of the corresponding end of the stick 10 in innermost position at the time on the supporting plates 30. By this movement of the center 81 from the right to the left the other end of the stick is forced into engagement with the toothed end of the corresponding spindle 80 and as the stick is now held by this pair of spindles and centers 80 and 81 it is evident that it is carried along by the same, and when the drums 50 and 51 next come to a stop the picked up stick is held in upper front position, as indicated in Fig. 5. The operator in charge of the machine pushes against the outermost stick 10 to move the innermost stick into final innermost position against the flanges 32 of the supporting plates 30. From the foregoing it will be seen that by the arrangement described the cutter heads 14 and 15 reduce two sticks while the drums 50 and 51 are at rest and a reduced stick is dropped during the revolving of the said drums, and the innermost stick on the supporting plates 30 is picked up by the corresponding pair of spindles and centers during the revolving movement of the drums.

When adjusting the drum 51 nearer to or farther from the drum 50 as above described for turning larger or smaller sticks, a corre-

sponding adjustment of the standards 39 on the guideway 40 is made, and when reducing sticks of different sizes in cross section the supporting plates 30 are transversely adjusted on the flanges 35 and the arms 36 are raised or lowered to hold the innermost stick in proper position for central engagement at the ends by the corresponding set of centers 81 and spindles 80 at the time the corresponding friction roller 157 drops off the abrupt upper end of the cam 158 as above explained.

It will be noticed that by the arrangement described no attention whatever is required on the part of the attendant in charge of the machine, and unskilled, cheap labor can be employed for placing the sticks successively in position on the supporting plates 30 and pushing the same rearwardly to be successively picked up on successive rotation of the drums 50 and 51.

It is expressly understood that the wood turning machine is entirely automatic in operation except as hereinbefore stated, turns out a large amount of work in a comparatively short time, and can be readily adjusted for turning sticks of different lengths and different sizes in cross section.

Having thus described our invention, we claim as new and desire to secure by Letters Patent:—

1. A wood turning machine, comprising revoluble cutter heads having their axes parallel, one of the cutter heads being adapted to reduce a portion of a stick to form a shank oval in cross section and to form a throat at one end of the shank, the other cutter head being adapted to reduce the portion of the stick adjacent the throat to form a head rectangular in cross section, an intermittently rotating work holder having two drums, one drum having one head slotted and the other both heads slotted, a series of spindles mounted to turn in one drum and passing through the slots thereof, a series of centers mounted to turn and to slide in the other drum and passing through the slots of the drum, corresponding spindles and centers being axially aligned and adapted to engage the ends of a stick while the latter is at rest, to rotate such stick and to carry it successively to the said cutter heads for the latter to reduce the stick while the work holder is at rest, means for gradually sliding the centers in one direction and rapidly and forcibly sliding them in the other direction, pattern guides on the said spindles and centers, and abutments at the said cutter heads and adapted to be engaged by the said pattern guides.

2. A wood turning machine, comprising a revoluble cutter head, a fixed support for the work to rest on, a work holder having two spaced connected drums between which extend the said cutter head and the said sup-

port, means intermittently rotating the said drums, a continuously driven shaft extending centrally through the said drums, sets of spindles and centers adapted to engage 5 the ends of the work while the latter is at rest on the said support and to carry the work to the said cutter head, spring pressed bearings for the said spindles and centers to turn in, the said centers being also mounted 10 ed to slide in the said bearings and the latter being mounted to swing in the said drums, gearings connecting the said shaft with the said spindles and centers to rotate the same, springs pressing the said centers 15 in the direction of their axes, cam arms for sliding the said centers, stationary cams engaged by the said cam arms, and guide pins on the said cam arms and engaging one of the said drums to guide the said cam 20 arms.

3. A wood turning machine, comprising a revoluble cutter head, a fixed support for the work to rest on, a work holder having two spaced connected drums between which 25 extend the said cutter head and the said support, one of the drums having one head slotted and the other both heads, the slots of one head having reduced portions, means intermittently rotating the said drums, a 30 continuously driven shaft extending centrally through the said drums, sets of spindles and centers adapted to engage the ends of the work while the latter is at rest on the said support and to carry the work 35 to the said cutter head, said spindles and centers projecting through the slots of the heads of the drums, spring pressed bearings for the said spindles and centers to turn in, the said centers being also mounted to slide 40 in the said bearings and the latter being mounted to swing in the said drums, gearings connecting the said shaft with the said spindles and centers to rotate the same, arms connected with the centers, stationary 45 cams engaged by the said arms and pins on the said arms and engaging the reduced portions of the said slots.

4. A wood turning machine, comprising a revoluble cutter head, spaced connected 50 drums, driving means intermittently rotating the said drums, a continuously rotating shaft extending centrally through the said drums, sets of spindles and sets of centers adapted to engage the ends of the work and 55 carry the latter to the said cutter head, the said spindles being journaled in one of the said drums, spring-pressed levers fulcrumed in the other drum and provided with bearings in which the said centers are 60 mounted to turn and to slide in the direction of their axes, the said centers extending through slots in the heads of the said drums to limit the swinging motion of the said levers, gearings connecting the said shaft 65 with the said spindles and centers, collars

on each of the said centers, a cam arm held loosely on each spindle and abutting against one of the collars, a stationary cam adapted to be engaged by the said cam arm, and a spring-pressed crosshead engaging the other 70 collar to hold the cam arm in engagement with the cam.

5. A wood turning machine comprising a revoluble cutter head, spaced connected drums, driving means intermittently rotating 75 the said drums, a continuously rotating shaft extending centrally through the said drum, sets of spindles and centers adapted to engage the ends of the work and carry the latter to the said cutter head, the said spindles 80 being journaled within one of the said drums, spring-pressed levers fulcrumed in the other drum and provided with bearings in which the said centers are mounted to turn and to slide in the direction of their axes, the said centers extending through slots in the heads of the said drums to limit the swinging motion of the said levers, gearings connecting the said shaft with the 85 said spindles and centers, springs pressing the centers in direction of their axes, a cam arm for moving each center against the action of its spring, a stationary cam adapted to be engaged by the said cam arm to operate the same, patterns secured on the said 90 spindles, and stationary guides adjacent the cutter head and adapted to be engaged by the said patterns.

6. In a wood turning machine, an intermittently rotating drum having slotted 100 heads, a slotted centering spindle mounted in the drum and projecting through the slots of the heads, spaced collars on one projecting end of the center, a cam arm on the said projecting end of the spindle, a stationary 105 cam adapted to engage the cam arm, and a spring-pressed crosshead engaging the other collar of the spindle.

7. In a wood turning machine, an intermittently rotating drum provided with 110 radial slots having one end reduced, a centering spindle mounted in the drum to turn and slide, spaced collars on the spindle, a cam arm loose on the spindle and having a pin adapted to project into the reduced portions of a slot of the drum, said arm abutting one of the collars of the spindle, a stationary cam engaging said cam arm, and a spring-pressed cross head engaging the other 115 collar of the spindle.

8. In a wood turning machine, a radially slotted drum, a driven shaft extending through the drum, levers pivoted within the drum intermediate of their ends, a spindle mounted in one end of each lever and extending through a slot of the drum, a spring secured to the other end of each lever and to the drum, and gearing between the said shaft and each spindle.

9. In a wood turning machine, a radially 130

slotted drum, a driven shaft extending through the drum and provided with a gear wheel within the drum, levers pivoted within the drum intermediate of their ends, a spindle mounted in one end of each lever and extending through a slot of the drum, a spring secured to the other end of the lever and to the drum, a pinion on the

spindle, a pinion on the pivot of each lever and meshing with the pinion of the spindle, 10 and a pinion in the drum and meshing with the pinion on the pivot of the lever and the gear wheel of the driven shaft.
